UNITED STATES PATENT OFFICE.

OTTO HEINS, OF NEW YORK, N. Y., AND CHARLES M. WILD, OF SPRINGFIELD, MASSACHUSETTS, ASSIGNORS TO BOSCH MAGNETO COMPANY, OF NEW YORK, N. Y., A CORPORATION OF NEW YORK.

MAGNETO.

1,225,330.

Specification of Letters Patent.

Patented May 8, 1917.

Application filed March 1, 1916. Serial No. 81,349.

To all whom it may concern:

Be it known that we, OTTO HEINS and CHARLES M. WILD, both subjects of the Emperor of Germany, residing in the city of 5 New York, county and State of New York, and city of Springfield, county of Hampden, and State of Massachusetts, respectively, have invented certain new and useful Improvements in Magnetos; and we do 10 hereby declare the following to be a full, clear, and exact description of the invention, such as will enable others skilled in the art to which it appertains to make and use the same.

15 The customary bipolar magneto producing two ignition voltages per rotation is unsatisfactory in electric ignition systems for high speed four-cycle internal combustion engines operating at 2500 to 3500 R. P. M. 20 and having four or six cylinders, and also for four-cycle engines operating at low speed and having many cylinders, such as twelve. This is due to the fact that the centrifugal force acting on the deflecting interrupter element sometimes causes the magneto to miss, and also the fact that the magneto gearing operates unsatisfactorily at 25 high speed. Magnetos producing four sparks per rotation have been designed to 30 overcome these disadvantages, but, although this type of magneto may be mounted directly on the crank shaft of eight-cylinder engines, magneto gearing is required for six and twelve cylinder engines.

35 The object of the present invention is to provide a magneto for high speed engines and particularly a magneto that can be driven directly from the crank shaft of a six or a twelve cylinder four-cycle engine. 40 In the preferred form of construction, we attain this result by a novel combination embodying a bipolar armature and a six-pole field member, the armature being of the ordinary shuttle form and the field member 45 being composed of three magnets of horse-shoe form arranged side by side along the axis of rotation of the armature and having poles disposed on diameters at 60° apart and embracing separate axial parts of the 50 armature. By providing a mechanical interrupter with six cams, and suitable distributing mechanism, the magneto may be mounted on the crank shaft of a twelve cylinder four-cycle engine; and by providing

three interrupter cams and suitable distributing mechanism, only the alternate ignition voltages that the magneto is capable of generating are utilized, so that the magneto is appropriate for mounting directly on the crank shaft of a six cylinder four-cycle engine. 55

In the accompanying drawings illustrating the preferred embodiment of our invention, in application, as an example, to a magneto generating three ignition voltages 60 per rotation, and having distributing mechanism driven at crank shaft speed for a six-cylinder four-cycle engine in order to eliminate the distributor gearing also,

Figure 1 is a central vertical section taken 70 longitudinally of the magneto; Figs. 2, 3 and 4 are sections on lines 2—2, 3—3 and 4—4, respectively, of Fig. 1; Fig. 5 is a front view of the mechanical interrupter with the cover removed; and Fig. 6 is a wiring diagram. 75

The armature core is of the ordinary shuttle type having a cross bar 1 connecting two polar projections 2, and is mounted for rotation in the bearings 3. The core is provided with a primary winding 4 and a secondary winding 5. 80

The field member is stationary and is composed of three permanent magnets 6, 7 and 8 of horse-shoe form, arranged side by side 85 along the axis of rotation of the armature, as shown. It will be observed that in the magnets 7 and 8 one arm is shorter than the other, the short arm 7' of the magnet 7 being on the same side of the magneto as the long arm 8'' of the magnet 8, while the long arm 7'' and the short arm 8' are on the same side. It will also be observed that the two arms 6' and 6'' of the magnet 6 are of the same length as each other, and of the same length as the long arms of the magnets 7 and 8. The magnet 6 is provided 90 with pole shoes 9' and 9'' disposed along the horizontal diameter of the armature, whereas the pole shoes 10' and 10'' of the magnet 7, and the pole shoes 11' and 11'' of the magnet 8 are disposed along the respective diameters at 60° to the horizontal, as indicated by the broken lines in Figs. 2, 3 and 4. It will also be observed that the magnets 6 and 7, together with their pole shoes 9', 9'' and 10', 10'', are wider measured along the axis of rotation of the armature. 100 105

ture than the magnet 8 and its pole shoes 11' and 11'', the result being that substantially equal ignition voltages are generated in each rotation. The adjacent magnet arms 6', 7' and 8'' are of one polarity, say north, while the other adjacent magnet arms 6'', 7'' and 8' are of the other polarity.

The mechanical interrupter for periodically interrupting the circuit of the primary winding 4 comprises the grounded interrupter element 12 and the insulated element 12', both mounted for rotation with the armature, and the three equally-spaced interrupter cams 13 carried by a normally stationary cam ring 14 provided with a lever 15 for adjusting at will the circumferential position of the cam ring to advance or retard the period of ignition throughout the timing range. One terminal of the primary winding 4 is connected to the insulated interrupter element 12', and the other terminal is grounded on the magneto frame. The coil condenser 16 is mounted fast with the armature and is electrically connected between the insulated interrupter element 12' and the magneto frame.

The two terminals of the secondary winding 5 are connected respectively to the axially-displaced distributor segments 17 and 17', which are embedded in two insulating rings 18 and 18' at 120° apart around the circumference. In order to provide for the required timing range, each of the segments is approximately 65° in extent. The distributor segments 17 and 17' are carried by the armature for rotation therewith and successively engage the three stationary pairs of spring-pressed brushes 19, 19' and 19'', which are individually connected to the insulated electrodes of grounded spark plugs.

The magneto shown may be driven directly from the crank shaft of a six-cylinder four-cycle engine. An ignition voltage is generated in the secondary winding 5 in those periods in which the polar projections 2 of the armature core bridge the spaces between the pole shoes of the magnets 6, 7 or 8, and in which the mechanical interrupter is opened at the time by reason of the engagement between a cam 13 and the deflecting interrupter element 12. Inasmuch as the pole shoes of the three magnets 6, 7 and 8 are disposed on diametrical lines at 60° to each other, each polar projection 2 will, during each half rotation of the armature, first bridge a space between the pole shoes of one magnet, then a space between the pole shoes of the second magnet at 60° from the first position, then a space between the pole shoes of the third magnet at 120° from the first position, then the other space between the pole shoes of the first magnet at 180° from the first position, and so on. In each position the polar projections of one

part of the armature bridge the spaces between the pole shoes of a single one of the magnets 6, 7 or 8, while the remaining portions of the polar projections register in part with the pole shoes of the other two magnets. The ignition voltage generated each time results from the simultaneous interruption of the primary circuit at the interrupter contacts and the diversion of the magnetic flux of one magnet from its prior path through the polar projections 2 and the cross bar 1 of the armature to the path across the polar projections alone, the time rate of change of the magnetic flux interlinking with the primary winding 4 being sufficient to generate a satisfactory ignition voltage in the secondary winding 5. The magnetic flux from the other magnets does not materially affect the ignition voltage generated at that time, because the path through the remaining parts of the polar projections 2 and the cross bar 1 remain substantially unchanged. In order to prevent the passage of magnetic flux from one to another of the magnets, it is preferable, though not essential, to magnetically insulate those parts of the armature core which coöperate with the pole shoes of the separate magnets, as, for instance, by means of the I-shaped brass members 20, and also to magnetically insulate the sets of pole shoes from each other and the magnets from each other by means of the aluminum members 21. The base 22, together with the side plate 23 carrying the interrupter housing and the side plate 24 carrying the distributor housing, are of non-magnetic material, as aluminum.

As a result of the fact that only three interrupter cams are provided at 120° apart, only three of the six ignition voltages that the magneto is capable of generating in each rotation, are generated, the alternate three being suppressed as a result of the fact that the primary circuit remains short-circuited by the interrupter element at the time that the magnetic flux from the magnets is diverted in its path through the armature core. However, it will be apparent that those ignition voltages would be generated by this magneto if six interrupter cams on 60° spacing were provided, together with suitable distributing mechanism, in which case the magneto could be mounted on the crank shaft of a twelve-cylinder, four-cycle engine to supply the six ignition voltages required per rotation of the engine. Furthermore, it will be apparent that the distributing mechanism shown herein may be variously modified, either by providing a distributor driven at half crank-shaft speed in the ordinary way to produce a spark at each spark plug in turn, or by means of distributing mechanism having an intermediate and a main distributor which, at each period of

ignition, conduct the ignition current to a single one of the spark plugs at a time, such, for instance, as disclosed in the copending application of Otto Heins and Victor W. 5 Kliesrath, Serial No. 75397, filed January 31, 1916, or in the application of Wolfgang E. Schwarzmann, Serial No. 78,489, filed February 15, 1916.

Having thus described our invention, 10 what we claim is:

1. In a magneto for electric ignition systems, a rotatable bipolar armature with polar projections, and a six-pole field member composed of three permanent magnets 15 having poles embracing different axial parts of the armature, the polar projections of the armature being designed to bridge the spaces between the poles of a single one of the magnets at a time.
2. In a magneto for electric ignition systems, a rotatable bipolar armature with polar projections, and a six-pole field member composed of three permanent magnets having poles embracing different axial parts 25 of the armature, the polar projections of the armature being designed to bridge the spaces between the poles of a single one of the magnets at intervals of 60°.
3. In a magneto for electric ignition systems, a rotatable bipolar armature with polar projections, and a six-pole field member composed of three permanent magnets having poles embracing different axial parts 35 of the armature, one axial part of the polar projections being designed to bridge the spaces between the poles of one of the magnets while the other axial parts simultaneously register with the poles of the other magnets.
4. In a magneto for electric ignition systems, a rotatable armature of shuttle form, and a six-pole field member composed of three permanent magnets each having poles embracing a different axial part of the armature. 45
5. In a magneto for electric ignition systems, a rotatable bipolar armature of shuttle form, and a six-pole field member composed of three horse-shoe magnets each having 50 pole shoes disposed on a diameter at 60° to the diameters of the pole shoes of the other magnets and embracing a different axial part of the armature.
6. In a magneto for electric ignition systems, a rotatable armature, and a six-pole field member composed of three horse-shoe magnets arranged side by side along the axis 55 of the armature and having poles embracing different axial parts thereof.
7. In a magneto for electric ignition systems, a rotatable armature, and a six-pole field member composed of three horse-shoe magnets arranged side by side along the axis of the armature, each magnet having 65 poles disposed on a diameter at 60° to the

diametrical disposition of the poles of the other magnets.

8. In a magneto for electric ignition systems, a rotatable armature, and a six-pole field member composed of three horse-shoe 70 magnets arranged side by side along the axis of the armature, one magnet having poles disposed on the horizontal diameter, and the other magnets having poles disposed on diameters at 60° to the horizontal diameter. 75

9. In a magneto for electric ignition systems, a rotatable armature, and a six-pole field member composed of three horse-shoe 80 magnets arranged side by side along the axis of the armature, one magnet having arms of equal length and poles disposed on the horizontal diameter, and each of the other magnets having a long arm and a short arm so arranged that the poles are 85 disposed on a diameter at 60° to the horizontal diameter.

10. In a magneto for electric ignition systems, a rotatable armature having three axial parts magnetically insulated from each 90 other, and a six-pole field member therefor composed of three permanent magnets having poles embracing the respective parts of the armature.

11. In a magneto for electric ignition systems, a rotatable armature, and a six-pole field member therefor composed of three permanent magnets having poles embracing different axial parts of the armature, the three magnets being magnetically insulated 95 from each other. 100

12. In a magneto for electric ignition systems, a rotatable armature, and a six-pole field member therefor composed of three permanent magnets arranged side by side 105 along the axis of the armature and having poles embracing different axial parts of the armature, and spacing members of non-magnetic material arranged between the magnets to magnetically insulate them. 110

13. In a magneto for electric ignition systems, a rotatable armature, and a six-pole field member therefor composed of three permanent magnets of horse-shoe form arranged side by side along the axis of the 115 armature with magnet arms of like polarity adjacent each other.

14. In a magneto for electric ignition systems, an armature core, a six-pole field member composed of three permanent magnets 120 each having poles embracing a different axial part of the armature core, and a generating winding mounted on the armature core in coöperation with the poles of the three magnets.

15. In a magneto for electric ignition systems, an armature core, a six-pole field member composed of three permanent magnets each having poles embracing a different axial part of the armature core, and a gen- 130

erating winding embracing the armature core in coöperation with the poles of the three magnets.

16. The combination with a magneto having a rotatable armature with primary and secondary windings, and a six-pole field member coöoperative with the armature, of spark plug distributing segments connected to the respective terminals of the secondary winding and carried by the armature at axially separated places.

17. The combination with a magneto having a rotatable armature with primary and secondary windings, and a field member coöoperative with the armature, of distributing mechanism comprising two segments connected to the respective terminals of the secondary winding and carried by the armature at axially separated places, and six stationary spark plug distributing brushes arranged in two circular series coöoperative with the segments.

18. The combination with a magneto having a rotatable armature with a winding thereon, and a six-pole field member coöoperative with the armature, of a mechanical interrupter having three interrupter cams to alter the circuit of the armature winding at three periods in each rotation.

19. The combination with a magneto having a rotatable armature with a winding thereon, and a six-pole field member coöoperative with the armature and capable of generating in the winding six ignition voltages per rotation, of a mechanical interrupter having three interrupter cams arranged to alter the circuit of the winding at alternate ones of the six periods at which the ignition voltages may be generated in each rotation.

20. The combination with a magneto having a rotatable armature with a winding thereon, and a six-pole field member coöoperative with the armature and capable of generating in the winding six ignition voltages per rotation, of a mechanical interrupter having three interrupter cams arranged to alter the circuit of the winding at alternate ones of the six periods at which the ignition voltages may be generated in each rotation, and distributing mechanism for distributing the ignition voltages generated in each rotation to spark plugs.

In testimony whereof we affix our signatures.

OTTO HEINS.
CHARLES M. WILD.
